UNITED STATES PATENT OFFICE

FREDERICK FITT, OF CHAUX-DE-FONDS, SWITZERLAND.

DETACHABLE WATCH-ESCAPEMENT.

SPECIFICATION forming part of Letters Patent No. 281,757, dated July 24, 1883.

Application filed September 18, 1882. (Model.)

To all whom it may concern:

Be it known that I, FREDERICK FITT, of Chaux-de-Fonds, in the canton of Neuchâtel, Switzerland, watch-maker, have invented certain new and useful Improvements in Watches and Time-Pieces; and I do hereby declare the following to be a full, clear, and exact description of the same.

My invention relates to detachable watch-escapements; and it consists in a novel construction of the same, whereby the escapement may be applied or removed without difficulty or loss of time, and in which the act of disconnecting the escapement bed or plate from the watch-frame also causes the center-wheel to be locked, and thus prevents the unwinding of the spring.

In the accompanying drawings, Figure 1 represents a face view of the rear face of the watch-movement with the escapement in position; Fig. 2, a view of the escapement detached and removed; Fig. 3, a face view of the back face of the watch-movement with the escapement removed; Fig. 4, a face view of the pillar-plate; Fig. 5, an edge or side view of the escapement; and Fig. 6, a perspective view of the locking slide and stop. All of the figures are enlarged to show the construction more plainly.

The present invention is designed as an improvement upon that for which Letters Patent were granted to me on the 20th day of July, 1880, and numbered 230,262, the object being to simplify and perfect the construction and to enable any form or pattern of escapement to be used, and of any height or thickness required without unduly increasing the thickness of the watch.

Referring again to the drawings, A represents the watch-movement as a whole; B, the pillar-plate; C, the back plate; D, the escapement as a whole, and E the center wheel of the watch.

The pillar-plate B is formed with an opening, *a*, at that point over which the escapement is placed, said opening being of the form shown more clearly in Fig. 3, one end being beveled as indicated. This opening is to receive the bottom plate or bed, *b*, of the escapement-platform F, said bottom plate or bed extending below the body of the platform

F, for the purpose of entering or passing through said recess, to secure and steady the plate in place and to give room for the necessary or desired length of escape and balance wheel spindles or shafts and other parts without unduly increasing the thickness of the watch. The lower plate or bed, *b*, carries the bearings of the escape and balance wheels, escape-lever, &c., while a balance-cock, *e*, and arm or supports *d* and *e* are provided to sustain the bearings of the upper ends of said parts, as usual. The bottom plate or bed, *b*, of the escapement-platform is furnished with a projecting finger or point, *f*, at one end, which is designed to engage with the pillar-plate and to assist in holding the escapement-platform in place, while the opposite end is beveled to fit the beveled end of opening *a*, as shown in Fig. 5. The end having the projecting nose or point *f* is first dropped into and through the opening *a*, and then the escapement-platform is moved a short distance longitudinally, causing the nose or point *f* to engage over the edge of the pillar-plate, as shown in Fig. 4, and just as the limit of movement is reached the beveled end of plate or bed *b* falls to the beveled seat formed for it at the end of opening *a*. The opening *a* being much smaller than the platform F, the latter rests upon the pillar-plate at each end, and at the side of the opening, and thus gets a firm broad bearing thereon, while being prevented by the close fitting of the bottom plate or bed, *b*, from shifting around thereon.

For the purpose of locking the escapement-platform firmly to the pillar-plate, I provide a slide, *G*, having a lateral projection, *g*, to enter a recess, *h*, in the side or edge of the escapement shown in Fig. 5, and thereby prevent the platform F from being raised or lifted out from the pillar-plate, upon which the slide G is mounted and held by a screw, *i*, and guide-pin *j*, as shown in Figs. 1 and 3. The slide G is furnished with a stud or knob, *k*, by which to move it back and forth, and has on its under or inner face, near its outer end, a pin, *l*, which extends through an opening in the pillar-plate, and projects slightly beyond the face of said plate to bear against the end of a spring, *H*, said end being formed with a double incline, *m*, so that by

moving the pin *l* to one or the other side of the angle of the double incline the pin *l* will be pressed and held in one or the other position. The movement of the pin in the manner stated is occasioned by the movement of slide *G* in one or the other direction, as already mentioned. When slide *G* is moved inward, the wing or projection *g* passes out of the notch *h*, leaving the escapement-platform 10 to be raised up and drawn off from the pillar-plate.

In order that the watch may not run down, and that it may not be necessary to unwind the spring before removing the escapement, the 15 slide *G* is furnished at its forward or inner end with a stop-pin, *n*, which, as the slide is moved inward, enters between the teeth of the center-wheel *E* and locks it against rotation, thus permitting the escapement to be removed 20 without affecting the condition of the spring. When the escapement is restored to place, the slide is drawn out to lock it in position, causing the pin *n* to be withdrawn from the teeth of wheel *E*, the wheels of the watch-train and 25 escapement being put into mesh in adjusting the escapement-platform to the pillar-plate.

I represents a screw having its head slightly rounded, which head forms a bearing for the point or finger *f*, the screw being turned in or 30 out to cause the escapement-platform to be drawn down more or less tightly by the point riding upon the head of the screw. Screws *o o*, near the ends of the escapement-platform, serve to adjust and steady the same, or to 35 prevent its tipping or rocking on the pillar-plate.

I do not claim herein a screw beneath the head of which the point or end of the escapement is held, as in my former patent above 40 referred to; but in this case the end of the platform, or the point formed thereon, rides over the head of the screw, and may be drawn off without turning the screw in the slightest degree.

45 Having thus described my invention, what I claim is—

1. In combination with a pillar-plate hav-

ing an opening in its face, and with an escapement-platform having a bottom plate fitting in said opening, a slide adapted to engage 50 with the platform and to hold it in place, substantially as shown and described.

2. In combination with pillar-plate *B*, and with escapement-platform *F*, seated thereon, slide *G*, adapted to engage with said platform 55 and lock it to the pillar-plate, substantially as shown and described.

3. In combination with a watch and with a detachable escapement applied thereto, a slide adapted to lock the escapement-platform in 60 place, and provided with a stop-pin to engage the teeth of a wheel of the watch, as and for the purpose set forth.

4. The combination, substantially as herein 65 described, of watch or movement *A*, detachable escapement-platform *F*, slide *G*, provided with pin *l*, and spring *H*, having double incline *m*, and bearing against pin *l*, substantially as and for the purpose set forth.

5. In combination with pillar-plate *B*, having 70 opening *a*, escapement-platform *F*, having point or projection *f*, and slide *G*, attached to the pillar-plate and adapted to lock the escapement-platform thereto, substantially as described.

6. In combination with pillar-plate *B*, having 75 opening *a*, and escapement-platform *F*, having point or projection *f*, screw *I* on the outer face of pillar-plate *B*, arranged directly beneath and in position to form a bearing for 80 said point, as shown and described.

7. In combination with a pillar-plate and a detachable escapement-platform, a slide *G*, adapted to lock the platform to the pillar-plate, and screws *o o*, passing through the escapement-platform and arranged to bear upon the pillar-plate, whereby the platform may be made firm and prevented from rocking or tipping.

FREDERICK FITT.
